Inventor
W.H. Borgers

By Clarence A. O'Brien

Attorney

UNITED STATES PATENT OFFICE.

WILLIAM H. BORGERS, OF MARION, SOUTH DAKOTA.

CORN-PLANTER WIRE.

Application filed June 23, 1925. Serial No. 39,095.

This invention relates to an improved corn planter wire, and has for its principal object to provide an extremely simple and inexpensive gage which serves to accurately indicate the degree of pull exerted upon the wire, whereby to permit the latter to be stretched sufficiently taut to provide a perfect guide in planting the rows of corn, thus eliminating the liability of crooked rows crosswise of the field.

To the attainment of the foregoing, the invention consists in the improvement as hereinafter described and definitely claimed.

In the accompanying drawings, forming part of this specification:—

Figure 1 is a perspective showing the manner of using the improved construction.

Figure 2 is an enlarged detail elevational and sectional view showing the particular construction.

Figure 3 is a detail perspective of the wire hook and indicator carrying rod comprised in my improvement.

Referring to the drawing in detail, the reference character 1 designates a metal stake which is pointed at its lower end to permit it to readily penetrate comparatively hard ground. At its top, the stake is provided with an eye 2, through which a rod or implement may be inserted to aid in withdrawing the stake from the ground. Attached to the central portion of the stake is a casing 3. On its face, said casing 3 is provided with graduations 4, indicating the number of pounds of pull. In the casing wall bearing said graduations in an elongated slot. Disposed within the casing 3 is a longitudinally slidable rod 5 provided at its outer end with a hook 6 and having its opposite end directed at right angles at 7. The extremity of the angularly directed end is flattened and provided with a polygonal aperture and the correspondingly shaped intermediate portion of an indicating arrow 8 is passed through this aperture. The casing 3 is formed at one end with an opening through which the rod is slid able, and a coiled spring 9 surrounds the rod, bearing at one end against the end of casing 3, and at its opposite arm against the angular end 7 of the rod. It will be noted that the indicating arrow extends crosswise of the slot, and serves to guide the inner end portion of

the rod; also, that the rod 5 and spring 9 are housed in casing 3 and are therefore protected against the weather. Appropriate loops 10 are provided at one end of casing 3 for fixedly securing the casing to the stake.

In practice, the stake is driven in the ground at one side of the field, as approximately indicated in Figure 1, then the corn planting guide wire 11 is secured to the hook 6 of the rod 5. The wire is pulled by any suitable means, and the degree of pull is registered by the cooperating indicating arrow and graduations. Ordinarily, a sixty pound pull will be found ideal for rendering the wire sufficiently taut to insure a straight row. The idea is of course to apply substantially the same degree of pull or stress to the wires for the formation of duplicate rows. Unless the wire is stretched substantially to the same degree each time, a crooked row might, and usually does, result. The gage will eliminate this, and a positively straight row is assured. It is of course understood that one or more wires and gages may be used as desired.

No doubt, an invention of this kind will be appreciated and clearly understood by those skilled in the art to which the invention relates. For this reason a more lengthy description is thought unnecessary.

While I have shown the preferred embodiment of my invention, it is to be understood that minor changes in the size, shape and arrangement of parts may be resorted to without departing from the spirit of the invention, and the scope of the appended claim.

Having thus described the invention, what I claim as new and desire to secure by Letters Patent is:—

A corn planter wire anchor and gauge, consisting essentially of a stake, a casing 95 having loops at one end thereof receiving the stake and also having an aperture in its opposite end and further having a longitudinal slot in one side wall and a row of graduations on the outer side of said wall in parallelism with said slot, a rod movable longitudinally and rectilinearly through the said aperture in the end wall of the casing and having means at its outer end for the attachment of a corn planter wire and also having 100 at its inner end a lateral arm extending 105

through and movable in the said slot of the casing and provided exteriorly of the casing with a vertically disposed aperture, an indicator carried in the said aperture of the latter arm and adapted to cooperate with the said graduations, and a spring surrounding the rod and housed with the major portion

of the rod in the casing and interposed between the said lateral arm of the rod and the outer apertured end of the casing.

10

In testimony whereof I affix my signature.

WILLIAM H. BORGERS.
